CLAIM

The ornamental design for a wearable fitness monitor, as shown and described.

DESCRIPTION

FIG. 1 is an isometric view of a wearable fitness monitor. FIG. 2 is a front view of the wearable fitness monitor of FIG. 1.

FIG. 3 is a back view of the wearable fitness monitor of FIG. 1.
FIG. 4 is a top view of the wearable fitness monitor of FIG. 1.

FIG. 5 is a bottom view of the wearable fitness monitor of FIG. 1.
FIG. 6 is a side view of the wearable fitness monitor of FIG. 1.

FIG. 7 is an opposite side view of the wearable fitness monitor of FIG. 1.

FIG. 8 is an off-angle view of the wearable fitness monitor of FIG. 1.
FIG. 9 is a different off-angle view of the wearable fitness monitor of FIG. 1.

FIG. 10 is an exploded view of the wearable fitness monitor of FIG. 1 that features a fitness monitor capsule and two flexible wristband straps; the flexible wristband straps of the wearable fitness monitor are configured to be removed from the fitness monitor capsule and are connectable together to form a wristband to allow the wearable fitness monitor to be worn on a person's wrist.

FIG. 11 depicts the location of the detail view of the wearable fitness monitor of FIG. 8 that is depicted in FIG. 12; and,

FIG. 12 is a detail view of the wearable fitness monitor of FIG. 11; this view stops at the circular boundary depicted in FIG. 11 and should not be viewed as indicating any particular limit of claimed or unclaimed subject matter.

The wearable fitness monitor depicted in the accompanying figures may be worn on a person's wrist.

Stipple shading is used in all of the accompanying Figures to convey surface contouring and not texture.

The broken lines shown in the drawings illustrate portions of the flexible wristband straps that form no part of the claimed design. Surfaces that do not include stipple shading and are bounded, at least in part, by broken lines form no part of the claimed design. Thus, for example, the logos, the cover on the underside of the fitness monitor capsule, the charging port on the underside of the fitness monitor capsule, the features within the cavities of fitness monitor capsule, and the buttons of the fitness monitor capsule, the holes on the straps, the peg, and the surfaces of the straps do not form part of the claimed design.
